(57) **CLAIM**

The ornamental design for a float for water quality equipment as shown and described.

DESCRIPTION

FIG. 1 is an isometric top view of a float for water quality equipment.

FIG. 2 is an isometric bottom view thereof.

FIG. 3 is a front view thereof; the rear view being a mirror image thereof

FIG. 4 is a left side view thereof.

FIG. 5 is a right side view thereof.

FIG. 6 is a top side view thereof; and,

FIG. 7 is a bottom side view thereof.

The broken lines in the figures are for the purpose of illustrating portions of the float for water quality equipment that form no part of the claimed design.

1 Claim, 7 Drawing Sheets
